INVENTOR:—

CHARLES HOWARD RODEBACK
BY *Martin P. Smith, Atty.*

UNITED STATES PATENT OFFICE

CHARLES HOWARD RODEBACK, OF SAN PEDRO, CALIFORNIA

NECKTIE

Application filed May 9, 1929. Serial No. 361,645.

My invention relates to improvements in neckties, particularly of the four-in-hand and bow types, and the principal objects of my invention are, to provide a tie that has its end portions differently colored or of different patterns, or composed of different and distinctive materials, and further to construct a tie of the four-in-hand type so that both ends shall be exposed to view when the tie is properly adjusted relative to the collar.

In the ordinary four-in-hand tie, the narrower end portion of the tie is positioned beneath the wider end and therefore it is hidden from view when the tie is worn.

To overcome this condition and permit both end portions of the tie to be exposed to view I propose to form in the wider end portion of the tie, near the portion that is formed in the knot, a narrow slit or opening, through which the narrow end portion of the tie may be drawn so that when the tie is properly adjusted upon the collar the narrow end portion overlies the wider end portion, thereby adding materially to the appearance of the tie.

A further object of my invention is to provide a tie of the four-in-hand type which does not necessarily require tying each time that it is put on, or untied each time that it is taken off, and to accomplish this result I arrange on the under side of the narrower end portion of the tie, adjacent to the end thereof, a transversely disposed stop that will be effective in preventing the narrow end portion of the tie being readily drawn entirely through the knot when the tie is being loosened in order to permit its removal from the collar.

With the foregoing and other objects in view, my invention consists in certain novel features of construction and arrangement of parts that will hereinafter be more fully described and claimed and illustrated in the accompanying drawing, in which:

Fig. 1 is a perspective view of a four-in-hand tie constructed in accordance with the principles of my invention.

Fig. 2 is a perspective view of the four-in-hand tie and showing the same tied or knotted for use.

Fig. 3 is an enlarged detail section taken on the line 3—3 of Fig. 1.

Fig. 4 is a front elevational view of a bow tie embodying the principles of my invention.

Referring by numerals to the accompanying drawing which illustrates a practical embodiment of my invention, 10 designates the wider end portion of the tie which may be constructed in the usual manner from any desired fabric; and connected in any suitable manner to the narrow end of the wider portion 10, is the inner end of the relatively narrow end portion 11 of the tie. The portions 10 and 11 may be differently colored, or formed of material of different or distinctive patterns, or said portions may be formed of different or distinctive materials.

Formed in the wider portion 10 of the tie at a point just below that portion that is formed into the knot when the tie is tied for use, is a slit or opening 12 and which slit is for the purpose of permitting the narrow end portion 11 to be inserted and drawn through the wide portion after the tie has been tied and thus the narrower portion of the tie will overlie the central portion of the wide end of the tie when the same is tied for use, as illustrated in Fig. 2.

Secured in any suitable manner, preferably by stitching on the rear face of the narrow portion 11 of the tie and adjacent to its outer end is a narrow transversely disposed member 13, preferably formed of fabric or suitable flexible material, which member functions as a stop, to prevent the narrow end of the tie from being wholly withdrawn through the knot when the tie is being removed from the collar. This member 13, in addition to performing the functions of a stop, may serve as a tag that bears the name of the manufacturer or retailer of the tie, or the trademark under which the tie is marketed.

By pulling the narrower portion of the tie upwardly through the knot until the stop 13 engages said knot, a relatively large loop is formed between the end portions of the tie and this loop permits the tie to be readily disengaged from the collar and removed by

passing the loop upwardly over the head of the wearer.

As a result of the construction just described it is not necessary to retie the knot each time the tie is applied for use, or to untie said knot each time the tie is removed from the collar.

In Fig. 4 I have illustrated a bow tie embodying the principles of my invention and where such construction is employed the end portions of the bow of the tie are differently colored or of distinctive appearance and when the ends are tied to form a bow the narrower end portion lies in front of the wider end portion, as illustrated in Fig. 4.

Thus it will be seen that I have provided a tie having portions of different colors or composed of different materials and which differently colored or distinctive portions are both exposed to view when the necktie is properly tied and worn. The narrow slit or opening in the relatively wide end portion of the tie, permits the opposite narrower end portion to be brought through the body at a point within or just below the knot, so that the differently colored or distinctive portions of the tie are displayed while the tie is worn, and such arrangement permits different and attractive color combinations to be produced, thereby adding materially to the appearance of the wearer.

The provision of the stop member on the rear side of the narrow end portion of the tie prevents said narrow end portion from being entirely drawn through the knot in the tie and consequently permitting the formation of a relatively large loop which may be readily removed from the wearer or adjusted without untying the knot.

It will be understood that minor changes in the size, form and construction of the various parts of my improved necktie may be made and substituted for those herein shown and described without departing from the spirit of my invention, the scope of which is set forth in the appended claims.

I claim as my invention:

1. As a new article of manufacture, a necktie having distinctively colored end portions of different widths, there being an opening formed through the end portion of the tie having the greater width for the accommodation of the narrow end portion of the tie and a flexible stop member secured to the rear face of the narrow end portion of the tie adjacent to the outer end thereof.

2. As an article of manufacture, a four-in-hand necktie having one relatively wide end portion and a relatively narrow end portion, which end portions are distinctive in appearance and there being an opening formed through that portion of the tie having the greater width adjacent to the point where the tie is knotted, which opening permits the narrower portion of the tie to pass through

the wider end portion of the tie and overlie the front surface thereof when the tie is knotted for use.

In testimony whereof I affix my signature.
CHARLES HOWARD RODEBACK.
